SOLDERING-IRON HOLDER AND HEATER.

1,162,972.

Specification of Letters Patent.

Patented Dec. 7, 1915.

Application filed March 16, 1914. Serial No. 824,901.

To all whom it may concern:

Be it known that I, TOM BRABSON, a citizen of the United States, and a resident of Brooklyn, in the county of Kings and State 5 of New York, have invented certain new and useful Improvements in Soldering-Iron Holders and Heaters, of which the following is a specification.

The invention pertains more particularly 10 to a gas furnace for holding and heating soldering irons, and resides in the novel features, structure and combinations of parts hereinafter described, and particularly pointed out in the claims.

One of the main objects of the invention 15 is to provide adequate means whereby the burner or burners of the heater are opened to the inflow of gas on the introduction of the iron or irons to the furnace and in which 20 the gas is automatically turned off from the burner or burners upon the withdrawal of the iron or irons from the furnace.

A further object of the invention is to secure the automatic turning on and off of the 25 gas without the use of springs, and generally speaking the purpose of the invention is to provide an efficient portable soldering iron heater of simple and comparatively inexpensive character.

The invention will be fully understood 30 from the detailed description hereinafter presented, reference being had to the accompanying drawings, in which:

Figure 1 is a vertical longitudinal section 35 through a heater constructed in accordance with and embodying my invention, a soldering iron being shown therein and the section being taken centrally through the roof of the furnace and, below said roof, on the 40 dotted line 1—1 of Fig. 2; Fig. 2 is a horizontal section through the same on the dotted line 2—2 of Fig. 1, and Fig. 3 is a vertical transverse section through the same on the dotted line 3—3 of Fig. 2.

In the drawings 10 designates the general 45 casing of the furnace, this casing comprising an exterior metal shell 11 and an interior lining of fire-proof material 12, and said casing is supported by a cast metal base 50 13 affording suitable legs 14. The base 13

is formed integrally with a central longitudinal bar 15 having transverse members 16 and with inwardly extending transverse arms 17 which extend inwardly from opposite sides of the base 13 and terminate in 55 near relation to the ends of said transverse members 16. The members 16 and arms 17 afford substantial supports for the soldering iron or irons to be placed within the furnace. In the construction shown two soldering irons may be introduced into the furnace, but I do not limit my invention to a construction adapted for two irons, since the furnace may be arranged to receive more than two irons or only one iron, as may be 60 preferred.

Below the adjoining ends of the arms 17 and members 16 are secured two longitudinal tubular gas burners 18, which correspond exactly with each other and are 70 formed with outlet orifices at their upper sides, as shown. The burners 18 are supported at one end by yokes 19 and at their other ends are secured to the cast base 13 by means of screws or bolts 20, and below the 75 burners 18 is provided a sheet metal bottom 21.

The burners 18 are provided on their outer ends with Bunsen burner attachments 22 of known character, and said burners are 80 supplied with gas from a main supply-pipe 23 and branch pipes or nozzles 24 leading therefrom into said Bunsen burner attachments. The pipe 23 is adapted to receive a flexible hose 25 leading from any suitable 85 source of gas supply, not shown. The branch pipes or nozzles 24 are provided with valves whereby they may be opened and closed, and these valves have projecting horizontal stems 26 upon which are secured 90 the outer ends of operating arms 27, which arms are utilized for opening and closing said valves and thereby turning on or turning off the flow of gas through the branch pipes or nozzles 24 to the burner 18.

The operating arms 27 extend slightly upwardly and inwardly through vertical slots 28 in the vertical wall of the furnace 10, and have upon their inner end metal hoods 29, these hoods being concaved on their lower 95 100

sides and deflected downwardly toward their outer ends and located directly over the burners 18. The operating arms 27 are each in one rigid piece of metal and operate as 5 crank arms for turning the valve stems 26 for turning on or turning off the flow of gas through the nozzles 24. I utilize the hoods 29 as the means for actuating the gas valve operating rods 27, and also for the 10 purpose of aiding in retaining the heat from the gas flames in close proximity to the soldering iron. When a soldering iron, one of which is shown in Fig. 1, is inserted into the furnace and upon the supports 16, 17 15 therefor, its front end is caused to ride against the hood 29 then in its lower position shown by dotted lines in Fig. 1, and elevate said hood and thereby through the rod 27 open the gas valve in the branch pipe 20 or nozzle 24. Upon the withdrawal of the soldering iron from the furnace the hood 29 and rod 27 turn to their lower position and thereby cut off the flow of gas through the branch pipe or nozzle 24. Normally, therefore, 25 the burners 18 have no gas in them, and gas is only admitted to said burners when soldering irons are placed within the furnace and by their introduction elevate the hoods 29. The hoods 29 and actuating 30 rods 27 are independent of each other so that either burner 18 may be employed without turning the gas into or off from the other burner.

The gas in the burners 18 and passing 35 from the orifices thereof may be ignited by any suitable means, but I prefer to provide pilot-light burners 30 for lighting the gas at the burners 18, said pilot-light burners being connected with the main supply pipe 23 40 by means of a branch pipe 31 in which I interpose an adjusting screw or valve 32 for controlling the flow of gas through said pipe 31.

The main features of the invention reside 45 in the provision of the hoods 29 and valve operating rods 27 for securing the automatic turning on of the gas when a soldering iron is placed in the furnace and the turning off of the gas automatically by the removal of 50 the soldering iron from the furnace. The downward deflection of the lower surfaces of the hoods 29 permits the soldering irons on their introduction to the furnace to assuredly elevate said hoods, and the 55 cavity of the lower surfaces of the hoods 29 enables the point of the irons to be readily engaged by the hoods even with some careless introduction of the irons to the furnace. The hoods 29 are elongated and 60 owing to their concavity and deflection serve, when in their upper position, as shields for holding down heat generated by the gas flames in proximity to the soldering irons. The hood members 29 will each preferably

be formed of cast metal and receive in a 65 hub thereon the valve actuating arm or rod 27, and said members will preferably be of sufficient weight to, upon the withdrawal of the irons, compel, without the use of springs, the closing of the gas valves. 70

What I claim as my invention and desire to secure by Letters-Patent, is:

1. A soldering iron heater of the character described comprising a general casing open at one end to admit the soldering irons 75 and substantially closed at the other end, a support for the iron within the lower portion of said casing, a gas burner extending below said support, a pipe for supplying gas to the burner having a controlling valve 80 provided with a horizontal stem and a main supply pipe connected with said valved pipe, and means for the automatic operation of said valve comprising a rigid actuating arm connected at one end with the stem of said 85 valve and extending thence through a slot in the closed end of the said casing and having rigidly connected with its end within the chamber of said casing a metal hood arranged directly over the burner and deflected downwardly at its outer end so that when a soldering iron is inserted on its support and pushed against said hood, the 90 downwardly deflected surface of the latter will serve as a cam coating with the iron to elevate the hood and through the rigid arm connected therewith turn the valve stem and open the valve, said hood being of sufficient weight to close the valve when left unsupported by the withdrawal of the iron 95 therefrom.

2. A soldering iron heater of the character described comprising a general casing open at one end to admit the soldering irons and substantially closed at the other end, a support for the iron within the lower portion of said casing, a gas burner extending below said support, a pipe for supplying gas to the burner having a controlling valve 100 provided with a horizontal stem and a main supply pipe connected with said valved pipe, and means for the automatic operation of said 105 valve comprising a rigid actuating arm connected at one end with the stem of said valve and extending thence through a slot in the closed end of the said casing and having rigidly connected with its end within the chamber of said casing a metal hood arranged directly over the burner and deflected downwardly at its outer end so that when a 110 soldering iron is inserted on its support and pushed against said hood, the downwardly deflected surface of the latter will serve as a cam coating with the iron to elevate the hood and through the rigid arm connected therewith turn the valve stem and open the valve, said hood being of sufficient weight to 115 close the valve when left unsupported by the

withdrawal of the iron therefrom, and said hood also having a concave lower side and adapted to serve as a shield for holding down heat generated by the gas flame in New York and State of New York, this 11th day of March, A. D. 1914.

TOM BRABSON.

5 proximity to the soldering iron.
